B. PORTER

LIGHT DEFLECTOR

Filed July 11, 1925

R. C. Thomas

Benjamin Porter, INVENTOR
BY Victor J. Evans

ATTORNEY

WITNESS:

UNITED STATES PATENT OFFICE.

BENJAMIN PORTER, OF FULLERTON, NORTH DAKOTA.

LIGHT DEFLECTOR.

Application filed July 11, 1925. Serial No. 42,956.

To all whom it may concern:

Be it known that I, BENJAMIN PORTER, a citizen of the United States, residing at Fullerton, in the county of Dickey and State of North Dakota, have invented new and useful Improvements in Light Deflectors, of which the following is a specification.

This invention relates to an improved lens for the headlamps of motor vehicles and the like, the general object of the invention being to provide a lens which will prevent blinding of persons on the road by the glare from the headlamps of the vehicle on which the lens are used while, at the same time, using practically all the light for illuminating the road ahead of the vehicle.

This invention is an improvement over that forming the subject matter of an application filed by me on January 31, 1925, Serial No. 6,106.

The present invention has an inwardly extending rib, or ribs, which is rendered opaque by a reflecting surface on its outer face, the rib being so placed that it will prevent the escape of those rays of light which would act to blind the driver of an approaching car or other persons, while causing these rays to pass through other portions of the lens for illuminating the road without blinding persons in front of the vehicle.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a sectional view through a headlamp showing my improved lens in use.

Figure 2 is a face view of one form of the improved lens.

Figure 3 is a view of another form.

Figure 4 is a view of a further form.

Figure 5 is a view of still another form.

Figure 6 is a transverse sectional view through the rib carrying part of a lens.

As shown in these views, I form the lens 1 with an inwardly extending rib 2 of V-shape in cross section with its outer faces provided with a coating 3 of reflecting substance (like mirrors). Thus the rib carrying part of the lens is rendered opaque, so that no rays of light can pass through, but the rays striking the rib will be deflected so that they will pass through another portion of the lens. The lens is shown in connection with a conventional form of headlamp A in Figure 1 and the rib is so located that it will prevent those rays of light from the lamp from escaping which would produce a glare and blind the drivers of vehicles approaching the vehicle equipped with the invention. The rib might be arranged in various positions in relation to the center of the lens according to the kind of lamp upon which it is used. For instance, Figure 2 shows the lens provided with a straight horizontal rib extending across the horizontal center of the lens. Figure 3 shows an inverted V-shaped rib 2' on the lens, while Figure 5 shows an arc-shaped rib 2'' on the lens. Figure 4 shows three radiating ribs 2^x and a central disk 4 from which the ribs radiate, this disk being of red or other color and acting to filter the rays passing through it. The top rib is made shorter than the other ribs. The rib, or ribs, may be arranged in a different manner from the illustrations, to suit the purpose in view.

As will be seen, the improved lens will provide a dark spot at the center of the light thrown off by the lamp into which one may look without being blinded, while the rays of light which are prevented from passing through this dark spot are deflected so that they will pass through another part of the lens to help illuminate the road or its vicinity so that practically all the light is made use of, while preventing blinding of persons approaching the light.

It is thought from the foregoing description that the advantages and novel features of my invention will be readily apparent.

I desire it to be understood that I may

make changes in the construction and in the combination and arrangement of the several parts, provided that such changes fall within the scope of the appended claim.

5 What I claim is:—

A lens for a headlamp having a number of inwardly extending ribs thereon arranged centrally of the lens, each rib be-

ing of V shape in cross section with its outer faces coated with reflective material 10 for preventing rays of light from passing through the rib and reflecting to other parts of the lens above and below the central portion thereof.

In testimony whereof I affix my signature.
BENJAMIN PORTER.
